United States Patent Office

Des. 204,864
Patented May 24, 1966

204,864

SHIRT

Lela Ruth Stewart, 420 Pearl St., La Jolla, Calif.

Filed July 12, 1965, Ser. No. 86,125

Term of patent 14 years

(Cl. D3—25)

FIG. 1.

FIG. 3.

FIG. 2.

I claim:

The ornamental design for a shirt, as shown.
